DRESSING MATERIAL FOR WOUNDS

Heinz Baron, Dusseldorf, Germany

Application November 5, 1954, Serial No. 467,049

Claims priority, application Germany October 11, 1954

10 Claims. (Cl. 139—413)

The invention relates to dressing material having but a slight sticking effect and consisting of threads and parts of threads respectively, which, when coming into contact with moisture emanating from wounds, extend, shrink or swell to different degrees and, thereby, execute movements contrary to each other, which movements decrease their sticking to each other or to their support or prevent it completely.

According to the form of execution of such wound textiles as already proposed in my copending application Serial No. 446,473, filed July 29th, 1954, now Pat. No. 2,802,464, neighboring weft threads are of different shrinkability when sucking up moisture emanating from wounds.

Considerably more favourable forms of tissues are obtained if, according to the invention, neighboring warp threads are of different shrinking, extending- or swelling capacities when in contact with moisture emanating from wounds. For it is much easier, during the weaving process, to make the warp threads take different positions in relation to the weft threads than vice versa. It is they that determine, for the main part, the kind of weaving and the possibility of an easy and different arrangement of the shrinkable and non-shrinkable parts in the woven fabric, in particular also with regard to the side of the tissue with which it is to be placed on the wounds.

As extensive experiments with animals have shown, it is advantageous for the healing process to prevent the shrinking or otherwise moving thread parts of the fabric from coming into contact with the surface of the wound. For this purpose, neighboring weft threads are alternately of larger or smaller cross sections. As a rule, the cross section is circular. The shrinkable thread parts carried near the wound surface, are carried round weft threads of a smaller cross section and are kept at a certain distance from the wound surface in consequence of the fact that the two neighbouring non-shrinkable warp threads are being carried round weft threads of larger cross sections. The varying shrinkability may not only be caused by a different lengthening of the threads, but also by a different twisting.

A little difference between the shrinkability of neighbouring warp threads suffices to show the inventive effect on contacting the tissue with moisture. As experiments have been shown, a very good effect is attained when the shrinkability is brought about by an overtwisting of the shrinkable warp threads by 2000 revolutions per meter and the moisture absorption being thus that a piece of the tissue according of the invention measuring 10 cm. long and 10 cm. broad can absorb 2 to 3 ccm. water, and is shortened by 10 to 15 per cent in the warp direction when dried in a not tensioned conditioned.

The threads of the dressing material to be used for wounds of normal secretion must have but a small sucking capacity, because it was found out by experiments that the healing process is broken by irritation of the wound in consequence of too great a sucking capacity of the fabric threads. The use of a double tissue having

2

upper and lower warp threads with two bands each of warp and of weft threads has proved to be of particular advantage and effect for the healing process, the upper tissue being interconnected to the lower one.

Whilst, according to the weight of the wound-textile, sixteen and more layers are required in the case of the mostly used muslin dressing material for obtaining a sufficient cover of the respective wound and a sufficient sucking capacity, a single layer of such a double tissue will be enough, if the individual threads, under observation of their mutual thickness ratio, are chosen at a corresponding thickness.

The use of such a double tissue entails a fundamentally new technique of dressing.

Other features of the invention are resulting from the following description of various examples of execution of the dressing material according to the invention.

In the accompanying drawing, the fabrics are shown schematically and as sections across the weft threads along the direction of the warp threads.

Fig. 1 representing a simple fabric having alternately thick and thin weft threads as well as alternately shrinkable and non-shrinkable warp threads,

Fig. 2 representing a double fabric with shrinking warp threads ascending and descending between the upper and lower tissue,

Fig. 3 representing a double fabric offering the possibility of being placed on the wounds from either side, with shrinkable warp threads ascending and descending between the upper and lower tissue,

Fig. 4 representing a double tissue, also offering the possibility of being placed on the wounds from either side, with interwoven shrinkable and non-shrinkable warp threads,

Figs. 5 to 7 representing double fabrics with the lower tissues free of shrinkable thread parts.

In the drawing, the shrinkable threads are represented by broken lines and the non-shrinkable threads by full lines.

The form of execution according to Fig. 1 is a simple fabric with alternately thick and thin weft threads 1, 2 of a circular cross section as shown in section in the drawing, and with shrinkable warp threads 3 and non-shrinkable warp threads 4 lying one adjacent the other. The threads are interwoven like the usual linen binding.

At the contact side 5 of the fabric with the wound surface, only the non-shrinkable warp threads 4 are coming into contact with the surface of the wounds, as, opposite to the surface of the wounds, the shrinkable warp threads 3 are carried round the weft threads 2 having a thinner cross section and, consequently, having a certain distance from the surface of the wounds. If moisture emanating from the wounds enters the tissue, the shrinkable warp threads 3 attempt to shrink and shorten, at the same time

drawing the thin weft threads 2 upwards and the thick weft threads 1 downwards. The non-shrinkable warp threads 4, too, are being influenced by the shrinking of the warp threads 3 loosening the thick weft threads 1 whereby the latter are permitted to move downwards with respect to the thin weft threads moving the shrinkable warp threads away from the wound. The shrinkage may also cause a turning of the threads round their axis.

If one imagines the fabric held at one place, a pull is exerted on the tissue by the shrinkage both at the right and left hand side of this spot, the upper parts of the shrinkable warp threads 3 consequently getting into a closer contact with their weft threads 1, whilst the contact between the lower parts of the non-shrinkable warp threads 4 and the weft threads 1 is loosened.

The shrinking movement of the warp threads 3 in the direction towards the spot, where the tissue is kept fast, causes, therefore, the weft threads 1 to be twisted and

taken along by friction, so that, in consequence of the shrinkage, they are slightly turned round their thread axis and, under certain circumstances, are even pressed together to an oval cross section.

The sticking process, in consequence of this opposite movement of the various thread parts, is interrupted, since it is a precondition for an effective sticking process that it is taking its course absolutely undisturbed. Whilst the thread parts are carrying out their various movements towards each other, new capillary spaces are being created that will not only take up and convey the moisture showing up from the wounds, but also capillary spaces filled with air are forming between the surface of the wounds and the fabric, and which spaces will very much favour the drying of the wounds.

Extensive comparative experiments have shown that wounds dressed with the dressing material according to the invention are drying and healing considerably faster than those, for which the common dressing material was used.

The form of execution as shown in Fig. 2 shows a double fabric having an upper tissue 6 and a lower tissue 7. The upper tissue consists of thick and thin weft threads 1, 2, and the lower tissue of thick and thin weft threads 1', 2'. The upper tissue contains non-shrinkable warp threads 4, and the lower tissue non-shrinkable warp threads 4', whilst the shrinkable warp threads 3 and 3' used are ascending and descending, as shown, between the upper and lower tissues, i.e., in such a manner that the shrinkable warp threads are carried round the thick weft threads 1 of the upper tissue and round the thin weft threads 2' of the lower tissue. As may be seen from the drawing, the non-shrinkable warp threads 4' are consequently projecting at the contact side 5, whereas all shrinkable thread parts of the warp threads 3 and 3' are receding from the surface of the wounds 5, since they are carried round the thin weft threads 2'. Binding of the upper tissue 6 with the lower tissue 7 is obtained by interlacing the warp threads 3 and 3' alternately with the upper and lower tissues.

In the case of the form of execution according to Fig. 3, the lower non-shrinkable warp threads 4 and 4' have the same position with regard to the thick and thin weft threads as in Fig. 2. It is true that the shrinkable warp threads 3 and 3' are ascending and descending between the upper and lower tissues 6 and 7, thus effecting the binding of the upper tissue to the lower one, however, they are both carried round the thin weft threads 2 and 2' in the upper as well as in the lower tissue. In consequence of this arrangement it is possible that not only the side 5 of the tissue, but also the other side 5' may be used as a contact face for the wound, since on both sides the thread parts of the shrinkable warp threads 3 and 3' are receding as compared with the non-shrinkable warp threads 4 and 4'.

The form of execution according to Fig. 4 differs from the form of execution according to Fig. 3 in that the shrinkable warp threads 3 and 3' are each only carried either through the upper or the lower tissue. Binding of the upper to the lower tissue is effected by carrying the warp threads 3 underneath the upwardly directed loops of the non-shrinkable warp threads 4' and interlacing them respectively. This dressing material, too, may be placed from either side on the wounds.

In the case of the forms of execution according to Figs. 5 to 7, the lower tissue to be placed on the wounds are kept completely free of shrinkable thread parts. In case of the tissue according to Fig. 5, the alternately thin and thick weft threads 1 and 2 of the upper tissue 6 are interlaced with the warp threads 3 and 3' lying one adjacent the other, whereas the lower tissue 7 consists accordingly of alternately thin and thick weft threads 1' and 2' and of the non-shrinkable warp threads 4 and 4' interwoven with them. Binding of the upper to the lower tissue is

effected in that non-shrinkable warp threads are carried, at intervals, round the thin weft threads 2 of the upper tissue.

In the case of the form of execution according to Fig. 6, the upper tissue is provided with thin weft threads 2 and the lower tissue with thick weft threads 1'. The shrinkable warp threads 3 and 3' are interwoven with the thin weft threads 2 in the upper tissue, whereas the thick weft threads of the lower tissue are interwoven with the non-shrinkable warp threads 4 and 4'. Also in this instance, binding is effected by the non-shrinkable warp threads 4 and 4' being carried, at intervals, above the weft threads 2 of the upper tissue.

In the case of the form of execution according to Fig. 7, provisions are made for thick weft threads 1 in the upper tissue 6, and for thin weft threads 2 in the lower tissue 7. The thick weft threads 1 are interwoven with the shrinkable warp threads 3 and 3'. The non-shrinking warp threads 4 are carried round the thin weft threads in the lower tissue and round the thick weft threads in the upper tissue.

In addition to the forms of fabrics as shown, numerous others may be formed similar to the well known twill and cloth bindings, the number of the bindings between the upper and the lower tissues to be increased or decreased at discretion.

The form of execution as shown in Fig. 2 may be altered in such a way that one shrinkable weft thread each 3 and 3' is interwoven with the upper or lower tissue and both are interlaced as shown for the threads 3 and 4' in Fig. 4.

The two shrinkable warp threads 3 and 3' of Fig. 3 may be carried in a corresponding manner.

In the case of the arrangement of the thick and thin weft threads of the upper and lower tissues each above the other as shown in Fig. 3, the shrinkable warp threads interwoven in the upper tissue may be interlaced with the non-shrinkable warp threads of the lower tissue as shown in Fig. 4 and vice versa.

The form of execution according to Fig. 7 may be changed in that the thick and thin weft threads are interchanged or that the shrinking and non-shrinking threads are interchanged. In the latter case the non-shrinkable threads are to be chosen of a considerably larger cross section than the shrinkable one, so as to guarantee that the former will cover the shrinkable threads and will keep them at a distance from the wound surface. On the whole, other varieties of the dressing tissue will result from different thicknesses of the threads chosen.

All the forms of execution explained show that the shrinkable thread parts are kept at a distance from the surface of the wound and, consequently, that an irritation of the wounds cannot be effected by them at all.

For this purpose, a difference in the thickness of the cross sections of the weft threads is not necessary in the case of the forms of execution according to Figs. 6 and 7, however, such a difference is applied all the same in order to favour the sucking process and the ventilation of the surface of the wounds. In the case of these examples of execution, the upper tissue is being stretched, as a whole, considerably as compared to the lower tissue, with the result that the lower tissue attempts to lift at the edges. Comparative experiments have shown that the sticking inclination of the fabrics explained amount only to $\frac{1}{10}$ of that of the usual muslin. The healing process will progress considerably faster than in the case of muslin, so much the more, as the wound, as mentioned already above, will dry out very quickly, due to the fact that the surface of the wound is well ventilated by the capillary spaces forming in consequence of the opposite movement of the thread parts. In this connection it may not be overlooked that, as a rule, the sucking capacity of the threads must be a small or a moderate one, because a great sucking capacity will cause an irritation of the wound. For this reason, unscoured

threads are used, i.e. such threads that have not yet lost their wax and pectine coat, in particular raw cotton. In the case of wounds producing an extraordinarily great quantity of secretions, such as purulent wounds, the use of a fabric is recommended having threads with an increased sucking capacity. To cover up and suck up the secretions of the wound, a single layer of the fabric is sufficient. The fabric, as a rule, is being woven in the shape of a band and is cut from the band according to the requirements. The dressing material may also be used in the form of large pieces for wounds having a large surface, as for instance for wounds caused by burning etc.

The band form permits a repeated application of the dressing material, as it can easily be cleaned and sterilized. After having been washed, the band is rolled up wet and under tension and is dried in this state. After being dried it shows the same effects as a new fabric.

The sterilization by means of steam will hardly decrease the shrinking effect, if the fabric is taken in a dry state from the sterilizer. A suitable dry-sterilization however, such as by means of ultraviolet rays is simpler and more practical.

What I claim, is:

1. Dressing material for a wound consisting of a double fabric having an upper and a lower tissue, each said tissue consisting of warp threads and weft threads, said warp threads being alternately of shrinkable and non-shrinkable capacity in reaction to wound moisture, said weft threads being alternately of large and small circular cross sections and means for interlacing said upper and lower tissues to one another.

2. Dressing material for a wound consisting of a double fabric having upper and lower tissues, each said tissue consisting of warp threads and weft threads, said warp threads being alternately of shrinkable and non-shrinkable capacity in reaction to wound moisture, said warp threads of non-shrinkable capacity forming a series of contact surfaces projecting from at least one of said tissues, said surfaces being adapted for contact with said wound.

3. Dressing material for a wound consisting of a double fabric having an upper and a lower tissue, said upper tissue including weft threads of small cross section and said lower tissue including weft threads of large cross section, said upper tissue further comprising warp threads shrinkable in reaction to wound moisture, said lower tissue comprising warp threads non-shrinkable in reaction to wound moisture, means interconnecting said upper and lower tissues comprising said warp threads of non-shrinkable capacity.

4. Dressing material for a wound consisting of a double fabric having an upper and a lower tissue, both sides of said fabric being adapted for wound contact, each said tissue including weft threads of alternately large and small cross section and further comprising warp threads alternately shrinkable and non-shrinkable in reaction to wound moisture, all of said shrinkable warp threads contacting the outermost sides of said weft threads of small cross section of said upper and lower tissues, said non-shrinkable warp threads of said upper tissue contacting the outermost sides of said weft threads of large cross section of said upper tissue, the said non-shrinkable warp threads of said lower tissue contacting the outermost sides of said weft threads of large cross section of said lower tissue.

5. Dressing material for wounds consisting of a double fabric having an upper and a lower tissue, each said tissue comprising weft threads of alternately large and small cross sections and further comprising warp threads alternately shrinkable and non-shrinkable in reaction to wound moisture, the said non-shrinkable warp threads in said upper tissues contacting the outermost sides of the weft threads of large cross section in said upper tissue, said shrinkable warp threads in each said tissue contacting the outermost sides of the weft threads of small cross section in both said upper and said lower tissues.

6. Dressing material for a wound consisting of a double fabric having an upper and a lower tissue, each said tissue comprising weft threads of alternately large and small cross sections and further comprising warp threads alternately shrinkable and non-shrinkable in reaction to wound moisture, the shrinkable warp threads of said upper tissue being interlaced with the non-shrinkable warp threads of said lower tissue.

7. Dressing material for a wound consisting of a double fabric having an upper and a lower tissue, each said tissue comprising weft threads of circular cross sections, said upper tissue further comprising warp threads shrinkable in reaction to wound moisture, means for connecting said tissues comprising warp threads non-shrinkable in reaction to wound moisture, said last-named warp threads engaging the outermost sides of weft threads in said upper and said lower tissue.

8. Dressing material for a wound, consisting of a double fabric having upper and lower tissues, each said tissue comprising weft threads of alternately large and small cross sections and further comprising warp threads alternately shrinkable and non-shrinkable in reaction to wound moisture, means interconnecting said upper and lower tissues comprising said shrinkable warp threads, said non-shrinkable warp threads in at least one of said upper and lower tissues projecting from said one tissue and forming surfaces adapted for contact with said wound.

9. Dressing material for a wound consisting of a double fabric having an upper and a lower tissue, said upper tissue including weft threads of alternately large and small cross sections and further including warp threads shrinkable in reaction to wound moisture, said lower tissue including weft threads of alternately large and small cross section and further including warp threads non-shrinkable in reaction to wound moisture, means interconnecting said upper and lower tissues comprising further warp threads of non-shrinkable capacity.

10. Dressing material for a wound consisting of a double fabric having upper and lower tissues, each of said tissues including weft threads, said upper tissue including a first set of warp threads shrinkable in reaction to wound moisture, said upper and lower tissues each including a second set of warp threads non-shrinkable in reaction to wound moisture and means interconnecting said upper and lower tissues comprising one of said sets of warp threads.
